UNITED STATES PATENT OFFICE.

GEORGE ALLEN LANE, OF PERRIS, CALIFORNIA.

INNER TUBE.

1,310,121.

Specification of Letters Patent. Patented July 15, 1919.

Application filed August 31, 1918. Serial No. 252,210.

To all whom it may concern:

Be it known that I, GEORGE ALLEN LANE, a citizen of the United States, residing at Perris, in the county of Riverside and State 5 of California, have invented certain new and useful Improvements in Inner Tubes, of which the following is a specification, reference being had to the accompanying drawings.

10 This invention relates to certain improvements in inner tubes for pneumatic tires and it is an object of the invention to provide a novel and improved inner tube which is non-elastic and which effectually serves to reduce to a minimum the possibility of a blow-out.

The invention consists in the details of construction and in the combination and arrangement of the several parts of my improved inner tube wherein certain important advantages are attained and the device rendered simpler, less expensive and otherwise more convenient and advantageous for use, as will be hereinafter more fully set forth.

20

25 The novel features of my invention will hereinafter be definitely claimed.

In order that my invention may be the better understood I will now proceed to describe the same with reference to the accompanying drawings, wherein:

30 Figure 1 is a fragmentary view in elevation of an inner tube formed in accordance with an embodiment of my invention, the outer lamination being partly wrapped; and

35 Fig. 2 is a transverse sectional view taken through the inner lamination of my improved tube with the coating applied thereto.

As disclosed in the accompanying drawings, my improved inner tube comprises an inner lamination of canvas, and said lamination 1 is sewed or otherwise held into the form of a continuous hollow tube. The inner face of the lamination 1 has applied thereto a coating 2 of rubber paint or the like which is applied thereto before the tube is formed and which serves to render the lamination airtight. A second strip or lamination 3 of canvas having its inner face provided with a coating of raw rubber is then wrapped around the tube formed by the lamination 1. It is preferred that the strip or lamination 3 be about three inches wide and of a length to permit about two inches of adjacent coils or convolutions to overlie

or overlap and to continue the wrapping 55 of the strip or lamination 3 until the same is of three thicknesses.

After the lamination 3 has been applied, the structure is placed in a suitable mold and suitably vulcanized.

60 The inflating valve V may be applied in any manner which best meets the requirements of practice.

It is preferred that the lamination 1 initially comprise a rectangular sheet of canvas of proper length and width and that the same be rolled transversely and to permit the desired connection by stitching or otherwise of the longitudinal marginal portions or the laminations 1 and after which the end 70 marginal portions or the rolled lamination are suitably secured by stitching or the like. After the longitudinal marginal portions and the end marginal portions have been suitably secured the same have applied 75 thereto a coating of liquid rubber or its equivalent to assure an airtight structure.

From the foregoing description it will be obvious that an inner tube constructed in accordance with my invention is particularly well adapted for use by reason of the convenience and facility with which it may be assembled and operated and it will also be obvious that my invention is susceptible of some change and modification without 85 materially departing from the principles and spirit thereof and for this reason I do not wish to be understood as limiting myself to the precise arrangement and formation of the several parts herein shown in carrying 90 out my invention in practice except as hereinafter claimed.

I claim:

As a new article of manufacture, an inner tube comprising an inner lamination of 95 textile fabric, a coating carried by the inner face of said fabric to make the same impervious to air, a textile strip wrapped around said inner lamination, and a coating carried by the inner face of said strip to 100 render the same impervious to air.

In testimony whereof I hereunto affix my signature in the presence of two witnesses.

GEORGE ALLEN LANE.

Witnesses:

M. A. WOLCOTT,
M. M. ROBERTS.
